Primary Examiner — Calvin E Vansant*Assistant Examiner* — Sydney M Evans(74) *Attorney, Agent, or Firm* — Ying-Ting Chen(57) **CLAIM**

The ornamental design for cordless pole saw, as shown and described.

DESCRIPTION

FIG. 1 is a front perspective view of cordless pole saw, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1;

FIG. 10 is an enlarged detail view of area 10 in FIG. 1;

FIG. 11 is an enlarged detail view of area 11 in FIG. 1;

FIG. 12 is an enlarged detail view of area 12 in FIG. 2;

FIG. 13 is an enlarged detail view of area 13 in FIG. 2;

FIG. 14 is an enlarged detail view of area 14 in FIG. 2; and,

FIG. 15 is a usage state view thereof.

The broken lines in the drawings illustrate the portions of the cordless pole saw, which form no part of the claimed design.
